UNITED STATES PATENT OFFICE.

RUSSELL HUFF, OF DETROIT, MICHIGAN, ASSIGNOR, BY MESNE ASSIGNMENTS, TO
PACKARD MOTOR CAR COMPANY, OF DETROIT, MICHIGAN, A CORPORATION OF
MICHIGAN.

HYDROCARBON-MOTOR.

1,208,969.

Specification of Letters Patent. Patented Dec. 19, 1916.

Original application filed July 2, 1909, Serial No. 505,735. Divided and this application filed March 29, 1912. Serial No. 687,204.

To all whom it may concern:

Be it known that I, RUSSELL HUFF, a citizen of the United States, and resident of Detroit, Wayne county, State of Michigan, 5 have invented certain new and useful Improvements in Hydrocarbon-Motors, of which the following is a specification.

The invention disclosed and claimed in this application which is a division of my 10 application Serial No. 505,735 filed July 2, 1909, relates to hydrocarbon motors and more particularly to motors having the sleeve type of valve.

One of the principal objects of the invention 15 is to provide a reciprocating member slidably fitted in another member so that the sliding member will not stick or seize, due to the expansion caused by subjecting one portion of the reciprocating member to 20 a greater temperature than another portion. This may be effected by making the clearance between the sleeve and adjacent members at a point where the heat of combustion is most severe greater than at other 25 points in the sleeve. As shown, the upper end of one of the sleeves is made a few thousandths less in diameter than the lower end. Another method of obtaining the desired result is to taper the sleeve toward the 30 upper end.

Other objects will appear from the following description taken in connection with the drawings which form a part of this specification, and in which:

35 Figure 1 is a vertical transverse section of a sleeve valve motor, and Fig. 2 is a detail view of one of the valve sleeves.

Referring to the drawings, 11 designates the upper section of the crank case provided 40 with integral side arms 12 for supporting the engine structure from the side bars of a motor vehicle, 13 the intermediate section, and 14 the lower section of the crank case. The crank shaft 15 is journaled in bearings 45 between the sections 13 and 11. All of the sections are bolted together in a manner well understood by those skilled in the art.

The cylinders 16 are bolted to the crank case. These cylinders in the construction 50 shown are cast in pairs. Each cylinder is provided with a cylinder head 17 provided with a downwardly extended portion 18 of smaller diameter than the internal diameter of the cylinder, thereby forming an annular

space or chamber 19. The downwardly projecting portion 18 is provided with the usual packing rings.

An inner valve sleeve 20 and an outer valve sleeve 21 are mounted to slide on each other in the cylinder. These valve sleeves 60 are provided with ears 22, and connecting rods 23 connect these ears with the eccentrics 25 mounted upon the valve shaft 24. These eccentrics are shown diagrammatically in Fig. 1 and are placed about eighty degrees 65 apart. The sleeves are provided with inlet ports 28 and exhaust ports 29, communicating with the inlet 30 and exhaust 31 respectively. The operation of the valves thus described will be obvious from the arrangement shown in Fig. 1.

The piston 43, which is of the usual trunk type, reciprocates within the inner sleeve 20 and is connected to the crank shaft 15 by means of the usual connecting rod 44. The 75 piston head is provided with an annular ledge 45, and with a series of holes 46 located above this ledge and communicating with similar holes 47 in the valve sleeves 20 and 21. The oil thrown up by the cranks 80 is caught by the ledge 45 and lubricates the sleeves.

Referring to Fig. 2, the valve sleeves are provided with a helical groove 70 communicating with the holes 47 hereinbefore described. The sleeves are also provided with transverse grooves 100 and 101 communicating by means of a groove 71, and a series of grooves 102 are provided communicating with the annular chamber 19.

In order to prevent the sticking of a valve sleeve due to unequal expansion a greater clearance is provided adjacent the ports or at the head end of the cylinder than at other portions thereof. One way to obtain this 95 unequal clearance is to form the sleeve with an external diameter at the head end C a few thousandths of an inch smaller than at the other end D, as shown in an exaggerated way in Fig. 1.

The same result may be obtained by tapering the sleeves toward the head or hotter end. It is obvious, however, that this taper need be only very slight.

From the foregoing description it will be 105 apparent that I have provided an exceedingly simple and very efficient means for preventing a member reciprocating in an

other member and subjected to a greater temperature at one portion than another, from sticking or seizing, due to expansion caused by the difference in temperatures.

5 Having thus described my invention, what I claim is:

1. In an internal combustion engine, the combination with a cylinder having a substantially uniform interior diameter throughout its length, of a substantially cylindrical valve fitted therein, the outside diameter of said valve being smaller at one end than at the other end, whereby a greater clearance is provided at one end than at the other end.
- 10 2. In an internal combustion engine, the combination with a cylinder having a substantially uniform interior diameter throughout its length, of a substantially cylindrical valve fitted in the cylinder, different parts of which are adapted to be subjected to different temperatures, the part which is subjected to the highest temperature having a smaller outside diameter than the other.
- 15 3. In an internal combustion engine, the combination with a cylinder having a substantially uniform interior diameter throughout its length, of a substantially cylindrical valve fitted therein, the head end of said valve being of smaller outside diameter than the other end whereby a greater clearance is provided at one end than the other end.
- 20 4. In an internal combustion engine, the combination of a cylinder member and a

sleeve member slidably fitted therein, said members formed with coöperating ports, the portion of the two members adjacent the ports being fitted with greater clearance than other portions, to allow for greater expansion.

5. In an internal combustion engine, the combination of a cylinder having a port, a piston working therein, a sleeve having a port and telescoped in said cylinder and surrounding said piston, said ports being adapted to coöperate to control the passage of gases therethrough, and said cylinder and sleeve being so formed as to provide a greater clearance adjacent said ports than at other portions of said sleeve and cylinder.

6. In an internal combustion engine, the combination with a cylinder having a substantially uniform interior diameter throughout its length, of a member fitted to reciprocate in said cylinder member and having a substantially cylindrical surface, the outside diameter of said surface adjacent one end of the member being less than at the other end, whereby a greater clearance is provided at the first mentioned end.

In testimony whereof I affix my signature in presence of two witnesses.

RUSSELL HUFF.
